UNITED STATES PATENT OFFICE.

JOHN HENRY WALKER, OF LEXINGTON, KENTUCKY.

LUBRICATOR.

SPECIFICATION forming part of Letters Patent No. 732,146, dated June 30, 1903.

Application filed November 24, 1902. Serial No. 132,531. (No model.)

To all whom it may concern:

Be it known that I, JOHN HENRY WALKER, a citizen of the United States, and a resident of Lexington, in the county of Fayette and State of Kentucky, have made certain new and useful Improvements in Lubricators, of which the following is a specification.

My invention is an improvement in lubricators especially designed for use on trolleys; and the invention consists in certain novel constructions and combinations of parts, as will be hereinafter described and claimed.

In the drawings, Figure 1 is a side view, and Fig. 2 an elevation, partly in section, of a trolley embodying my invention. Fig. 3 is a cross-sectional view on about line 3 3 of Fig. 2. Fig. 4 is a detail view showing the slotted construction at the end of the harp-prongs. Fig. 5 is a detail perspective view of one of the lubricating-boxes, showing the lug and pin thereon for entering the slot and opening in the harp-prong; and Fig. 6 is a detail sectional view on about line 6 6 of Fig. 1, showing the harp-prong and the lubricating-box with its lug fitted in the slot of said prong.

In carrying out my invention I provide the lubricating devices in connection with two boxes providing the bearings for the opposite ends of the wheel-shaft and support these boxes in the harp-prongs and hold them from turning by the mechanism which will be more fully described hereinafter.

The harp A has its prongs B spread apart at their front ends, and they are provided in their said front or free ends with slots B', through which the lubricating-boxes, with the connecting parts, are inserted in assembling the parts. These lubricating-boxes C are provided with bearings for the axle of the trolley-wheel and may be inserted bodily in the slots B', and when secured by the cap-nuts, presently described, to their respective prongs and the opposite cap-nuts are connected by the tie-rod the wheel and the associated parts will be firmly held in the harp, as desired.

The prongs B are provided with the slots B', leading from their edges, and also with the perforations B², the slots B' receiving the lugs C' on the lubricating-boxes C and pins C² on such boxes entering the openings B² in the

prongs B, as will be understood from Figs. 1 and 2.

The wheel D has fixed in its center the tubular axle D', which in the use of the trolley makes contact at its opposite ends with the contact-plugs E, which are in the form of rings, as shown, and are held in close contact with the ends of the tubular axle D' by the means presently described.

The boxes C are provided at their outer ends with the projecting tubular tenons C³, which are threaded externally to receive the cap-nuts F and whose bores are sufficiently large to receive the contact-plugs E, which fit in said bores, as shown in Fig. 2. At the inner ends of the bores of the said tenons the outer cap-section of the box C is provided with the rabbet or groove F', in which fits the inner section of the box C, which section has the tubular central bushing portion C⁴, held at its outer end in the rabbet F', and the inner face-plate, which fits at its outer edge in a groove C⁶ in the inner end of the outer tubular portion of the outer section of the box C. I thus make the box C with an outer or cap section and with an inner section, which latter comprises an inner face-plate and the central tubular portion held to the cap-section, the inner face-plate C⁵ being fitted at its outer edge to the cap-section and pressed in contact therewith by a few strokes of a hammer or otherwise to properly unite the parts.

The tubular portion C⁴ has its bore grooved—it may be spirally, if preferred—and in the groove C⁷ so formed I supply graphite or similar material to insure lubrication of the axle D' in case the oil should fail for any reason. This tube C⁴ has a slot G formed through it leading to the axle D', and a felt or other absorbent pad H fits in the oil-chamber I within the box C and has a tongue H' passing through the slot G and into contact with the axle D', so the oil can be supplied by capillary attraction to the axle D'. The wick-like portion H' is held in the slot G by means of the pin G', as best shown in Fig. 3, so the said wick cannot be displaced. By this means oil supplied to the chamber I through the opening covered by the cap I' can be fed evenly to the axle D', as desired.

As shown in Fig. 2, the contact-ring E fits within the bore of the tubular tenon of the

lubricating-box, and a short tube or thimble K bears against the said contact-plug and is pressed firmly thereagainst by the cap-nut F, which is threaded on the tenon C³ up against 5 the harp-prong, as shown in the said Fig. 2, thus securing the box to the harp and also pressing the thimble K firmly against the contact-plug and holding the same in contact with the tubular axle or wheel when the opposite cap-nuts are secured by the tie-rod L. This tie-rod L extends through the tubular axle D' and through openings f in the cap-nuts F and receives the nuts L', whose heads sit in grooves f' at the outer ends of the opening f and against gaskets D² to prevent the wasting of oil.

The felt wick H' not only aids in feeding the oil to the bearing, but prevents the oil from wasting by passing too rapidly to the bearing.

Having thus described my invention, what I claim as new, and desire to secure by Letters Patent, is—

1. The combination of the wheel, the axle 25 projecting from the opposite sides of the wheel, the lubricating-boxes having tubular portions fitting on the axle and also provided with oil-cavities surrounding such tubular portions, and having the tubular portions provided at 30 their under sides with slots or openings, and the lubricating-wicks having body portions fitting in the oil-cavity and other portions fit-

ting in the slots or openings in the tubular portions of the lubricating-boxes, the pins for securing such wicks in such slots and supports for the lubricating-boxes substantially as set forth.

2. The combination with the wheel and the axle to which the wheel is fixed of the boxes arranged alongside the wheel and having a tubular portion or bushing fitting said axle and an oil-cavity surrounding said bushing, the bushing being provided with an opening connecting said cavity with the bearing for the wheel-axle, and the wick having a portion fitted in the oil-cavity and the portion fitted and held in the opening leading to the bearing for the axle, substantially as set forth.

3. The combination of the wheel, the axle fixed to and projecting from the wheel and the lubricating-boxes on opposite sides of the wheel and comprising each a cup-section and an opposite section having a face-plate and a central tubular portion held to the cup-section and provided with a slot or opening for the wick, and the wick having a body portion fitted in the oil-cavity surrounding the tubular portion of the lubricating-box, and a portion fitted in the slot of such tube substantially as set forth.

JOHN HENRY WALKER.
